No. 613,832.

Patented Nov. 8, 1898.

G. R. WILLIAMS.
DATE TYPE HOLDER.

(Application filed Oct. 28, 1897.)

(No Model.)

UNITED STATES PATENT OFFICE.

GEORGE R. WILLIAMS, OF ALBANY, MISSOURI.

DATE-TYPE HOLDER.

SPECIFICATION forming part of Letters Patent No. 613,832, dated November 8, 1898.

Application filed October 23, 1897. Serial No. 656,152. (No model.)

To all whom it may concern:

Be it known that I, GEORGE R. WILLIAMS, residing at Albany, in the county of Gentry and State of Missouri, have invented a new 5 and useful Date-Type Holder, of which the following is a specification.

This invention relates to type-cabinets; and the object of the same is to provide a cabinet for the purpose of holding the dating-type so 10 that they may be quickly and readily withdrawn therefrom in proper order for use in printing the month, day, and hour upon articles requiring the same.

With the above object in view the invention 15 consists of a plurality of chambers open at their upper ends and of such a size as to receive the proper number of type for the months, days, and hours, said type being placed in the chambers on end, and drawers 20 at the lower ends of the chambers to receive the type, said drawers being so constructed that it is impossible to remove them until the last type has been withdrawn from the chamber, thus preventing the drawers from being 25 accidentally entirely withdrawn, but permitting the removal of the same for cleaning or other desired purposes.

The invention consists also in certain other 30 details of construction, which will be hereinafter described in the specification and pointed out in the claims.

In the accompanying drawings, Figure 1 is 35 a perspective view of my cabinet. Fig. 2 is a vertical longitudinal sectional view. Fig. 3 is a perspective of Fig. 2, showing one of the drawers partially withdrawn. Fig. 4 is a transverse section on line 4-4 of Fig. 2. Fig. 5 is a similar view taken on line 5-5 of Fig. 2. Fig. 6 is a perspective view of one of the 40 drawers.

Referring to the drawings, A indicates the supporting-board, which is perforated adjacent its ends at B to receive attaching nails or screws, by means of which the cabinet is 45 secured in position upon the wall or other supporting object. Upon the front side of the supporting-board is a casing C, forming a chamber, and formed upon the front wall of this casing are the type-chambers D, which 50 are open at their upper ends to receive the type. The upper end of the central chamber extends above the side chambers, and said

chambers are also of different lengths, according to the number of type to be held thereby, the central chamber being in this 55 instance of sufficient length to contain the type representing the months, while the two side chambers are of such size as to accommodate the days and hours, respectively. The front and rear wall of each chamber at the 60 lower end thereof is formed with an opening to receive a drawer E. This drawer E is of such length as to extend back into casing C when closed and abut against the supporting-board. The front half of the drawer is 65 formed into a receptacle F, open at its top to receive the type from the chamber and of such size as to accommodate one type on edge, the side walls of the drawer-compartment being cut away at their upper edges, so that the 70 type may be readily removed therefrom.

The rear portion of each drawer is closed, as illustrated at G, and projecting from the upper rear edge thereof is the stop H.

The drawer-openings are of such size as to 75 permit the drawer and stop to pass therethrough and the drawer to be entirely withdrawn for the purpose of cleaning the same and the type-chamber; but when the type are placed in the chamber on edge and the 80 drawer withdrawn far enough to remove the type from the drawer-compartment a second type is resting upon the closed portion G of the drawer, and by the engagement of the stop with this type the entire removal of the 85 drawer is prevented.

In operation the type representing months, days, and hours are placed in their respective chambers, one upon the other in proper succession. By withdrawing the drawers the 90 desired type can be quickly obtained, and after using the same they are deposited in the open end of the chamber to be ready for use when the same month, day, or hour again is reached.

The cabinet is extremely simple in construction, yet very effective in operation, and may be constructed of either wood or metal, as desired.

Having thus fully described my invention, 100 what I claim as new, and desire to secure by Letters Patent of the United States, is—

1. A type-cabinet comprising a type-chamber, a drawer therein adapted to remove the

- type successively therefrom, and means for preventing the entire removal of the drawer until all the type in the chamber have been withdrawn, substantially as described.
5. 2. A type-cabinet comprising a chamber adapted to contain the type, one upon the other, a drawer therein for removing the type one at a time therefrom, and a stop for said drawer adapted to engage the next successive type and prevent the entire removal of the drawer when the latter is drawn out to remove a type, substantially as described.
10. 3. A type-cabinet comprising a chamber adapted to hold the type, one upon the other, a drawer having a compartment formed in its front portion of such size as to receive a single type, said drawer being positioned in the chamber, the rear portion of the drawer being closed, so that when the drawer is drawn out to remove a type, the next successive type will rest upon the closed portion, and a stop adapted to engage the type resting upon the closed portion of the drawer and prevent the
- entire removal of the latter, substantially as described.
4. A type-cabinet comprising a casing, a plurality of type-chambers formed on the front side of the casing and open at their upper ends, said chambers being of such size as to receive the type one upon the other, 30 drawers at the lower ends of said chambers, said drawers having compartments adapted to register with the chambers when the drawers are closed and receive one of the type, and also closed portions which project 35 into the casing when the drawers are closed but which register with the chambers when the drawers are opened, the next type resting upon these closed portions, and stops adapted to engage the type resting on the closed portions of the drawers to prevent the withdrawal of the latter, substantially as described.
